CLAIM

The ornamental design for a night light, as shown and described.

DESCRIPTION

FIG. 1 is a perspective view of a night light showing my new design;

FIG. 2 is a front elevational view thereof;

FIG. 3 is a rear elevational view thereof;

FIG. 4 is a side elevation view thereof;

FIG. 5 is a top elevational view thereof; and,

FIG. 6 is a bottom elevational view thereof.

The broken line shown in each of FIGS. 1-6 is for illustrative purposes only and forms no part of the claimed design.
